UNITED STATES PATENT OFFICE.

AUBREY E. MEYER, OF WHITE PLAINS, NEW YORK.

COMBING DEVICE FOR TEXTILE FIBERS.

Continuation of application Serial No. 162,602, filed April 17, 1917. This application filed August 29, 1918, Serial No. 251,930. Renewed February 24, 1922. Serial No. 539,038.

To all whom it may concern:

Be it known that I, AUBREY E. MEYER, a citizen of the United States, and a resident of White Plains, county of Westchester, and 5 State of New York, have invented certain new and useful Improvements in Combing Devices for Textile Fibers, of which the following is a specification.

My invention relates to a combing device 10 for textile fibers, and the objects of the invention are—

To provide a combing device the use of which will result in a reduction of the amount of fiber of the proper length and 15 quality that is torn, cut or combed away in combing operations.

To provide a combing cylinder or series 20 of combing cylinders, as may be desired, capable of yielding about its axis or their axes when the fiber being engaged by the teeth is put under such tension as to result 25 in unduly tearing or cutting the fiber, or in combing out an unnecessary amount of fiber from the tufts or stock of fiber being combed.

To provide a combing cylinder or series of 30 cylinders in which the yielding movement may be regulated according to the particular use to which the device is put.

To provide a combing cylinder divided 35 into a number of combing sections or disks which are yieldable with respect to each other so that if one or more disks engage fiber which gives such resistance to combing that the disk is caused to yield about its axis, such disk may yield without affecting or unduly affecting the others; and

To provide a combing machine in which a 40 combing device of the above character may be utilized to do the preliminary combing in combination with a non-yieldable combing cylinder that continues the combing.

For the sake of brevity, I have referred to 45 the device as a combing device or cylinder for textile fibers, but I use the word "combing" in its broadest sense, as including the various operations for taking the tangle or snarl out of fiber, for separating or opening up fiber in any state, and the like. Various 50 terms are given to these operations in the art depending upon the specific stage of the treatment of the fiber at which the

operation is performed, and sometimes upon the character of the fiber. In the stricter and more technical sense, some of these 55 operations are referred to as combing, carding, opening, dressing, etc.; but in each of these operations the fibers are "combed" in the broad sense of the term, and the device used is, in the broad sense of the term, a 60 combing device—i. e., it has projections suitable to the particular use, which I will refer to as teeth, that engage the fibers to remove the tangles, separate the fiber, smooth or assist in smoothing it out, clean it, or 65 cause the fibers to lie more parallel, etc.

In some of these combing operations the fiber remains on its supporting cylinders or holding frame, as hereinafter illustrated, and the combing teeth of one or more cylinders merely pass through the fiber, while in other combing apparatus the fiber is combed or removed from one toothed cylinder or from between two toothed cylinders onto another toothed cylinder, such for example as in certain fiber-opening machines one of which is hereinafter illustrated. The cylinders are substantially the same in construction whether used to feed the fibrous material or fiber (as for example in the 70 form of "laps") to other toothed cylinders, or used so as to have their teeth passed through the fiber while it is held on some support. These cylinders have numerous 75 teeth set in suitable material such as leather 80 stretched over the cylinders, and it will be apparent that, in machines using the toothed holding or feeding cylinders for holding the fibers in position to be acted upon by another toothed cylinder, the combing advantages 85 of the invention will to some extent be acquired by having either the feed cylinders themselves or the one acting upon the fiber which is held by the feed cylinders, made 90 yieldable; that is to say, the destruction of 95 fiber in either case will to some extent be prevented. It will therefore be understood that my invention is capable of being used in any of these operations, and that I refer to it as a combing device regardless of which 100 of these forms it takes, or which of the numerous uses it may be put to.

Likewise, with regard to the character of fiber to be treated by my machine, while the

invention was devised particularly for combing silk fiber and ramie, and while that may be its most important use, nevertheless, I do not wish it understood that the invention is to 5 limited to combing these or any other particular species of fiber, as the invention is useful for combing various fibers natural or artificial.

Further objects and advantages of the 10 invention will more fully appear from the following description taken in connection with the accompanying drawings illustrating preferred forms of the invention, and in which—

15 Fig. 1 is an end elevation of a combing machine embodying my invention;

Fig. 2 shows one of the combing cylinders of Figure 1 embodying one form of the invention;

20 Fig. 3 is an enlarged sectional view of the cylinder shown in Figure 2, with the central part broken away;

Fig. 4 is a sectional view of a part of a modified form of cylinder embodying the 25 invention;

Fig. 5 shows an end view of another form of the invention; and

Fig. 6 shows another form of combing machine embodying my invention.

30 Referring to the drawings, 1 is the frame of a combing machine having a platform 2 for the operator, and having a rotating cylinder 3 fitted with suitable sets of clamps 4 to hold the rods or sticks 5 charged with 35 the fiber or stock 6 to be combed. This cylinder is driven from shaft 7 through the intermediation of a belt 8 driving pulley 9 mounted on shaft 10 which, through the worm gears 11 shown, rotates said cylinder.

40 The machine so far described is a well-known type of combing or dressing machine, known as the Brenier, Neyret & Co. machine, and sometimes as the Brenier machine, and is shown in one embodiment in 45 Italian patent entitled "Perfectionnements aux machines peigneuses circulaire pour les dechets de soie," granted to Brenier et Compagnie March 30, 1878, the text of which patent is found in "Bollettino della Privata Industriale, Anno 1878," at page 237, 50 2A series, vol. 9, No. 189, and the drawing of which is found in "Tavola XIIX, vol. 9, part 1". The machine is also shown and described in part on page 462 of the publication by J. Zipser, entitled "Textile raw materials", etc., published in London in 1901, by Scott, Greenwood & Son, 8 Broadway, Ludgate Hill, E. C. The manner of placing the fiber between the clamps, and

55 60 65 70 75 80 85 90 95 100 105 110 115 120 125 placing the fiber while the machine is rotating, and of taking the combed fiber out of the machine, is all well understood in the art and therefore will not be described herein.

65 Such a machine usually has two combing

cylinders or doffer rolls such as 12 and 13, provided, respectively, with combing teeth 14 and 15, sometimes known as "brushes." These teeth, as is well understood, are usually set in a leather or rubber blanket secured 70 around the periphery of the cylinder so that the individual teeth yield slightly when engaging an obstruction, but not enough to prevent serious and undue tearing or combing out of good fibers when snarls, etc., are 75 encountered. These cylinders are positively driven by any suitable mechanism, such as belts or the like, just as they have been heretofore driven in machines of this general type; and in combing the fiber or stock, they

naturally comb or tear through any snarls or entanglements or other obstructions, and thus pull out and cut an unnecessary amount of good fiber.

To obviate this, I provide a preliminary combing device which, in the 80 form shown in Figure 1, consists of a suitable support or frame 16 rotatably mounted on a shaft 17 driven by a belt 18 running over pulley 19 mounted on shaft 20 of combing cylinder 13, and over pulley 21 mounted 90

on said shaft 17. The frame 16 comprises two end spiders (only one of which is shown) suitably connected and carrying a series of relatively small combing cylinders 22, in this instance four. The cylinders are 95 mounted on their frame or support in any suitable way so that each may yield about its axis when encountering undue resistance in combing the fibers. This may be accomplished in any suitable way, as for example by taking a plain unsectionalized combing cylinder 22' and mounting it in split friction bearings 25, as shown in Figure 5. The bearing consists of an upper bearing portion 26 hinged at 27 to the lower bearing portion 28 formed on the arm 29 of the spider or frame, and the bearing is lined with any suitable material 30 that will give the desired friction, such as babbitt. The cylinder 22' shown in Figure 5 is rotatably 100 mounted in said bearing, so that it can yield when encountering a certain amount of resistance in the combing operation, and its yielding movement is regulated in this instance by the nut 31 threaded on a bolt 32 105 with a spring 33 between the nut and the upper bearing member 26. By screwing this nut up or down, the amount of friction in the bearing is reduced or increased to adjust the amount of resistance which the combing 110 cylinder will stand before it yields about its axis. This is so adjusted that the cylinder will yield whenever such undue tension is put on the fibers as will tend to unnecessarily tear, cut or break them in the combing operation.

These small cylinders when arranged and used in the manner shown, are approximately three to four inches in diameter, and are mounted on a frame of such size that the diameter of the frame and 115 120 125 130

cylinders is approximately eighteen to twenty inches, or approximately equal to the diameter of the other combing cylinders 12 and 13; although these dimensions may be varied as and according to the purposes desired.

A roller brush 35 is mounted as an idler on shaft 36 between the frame 16 and the combing cylinder 13, and the bristles of this brush are in such intimate contact with the teeth 15 on combing cylinder 13 that the roller brush is driven at substantially the same peripheral speed as that of the combing cylinder 13, and this peripheral speed is made greater than that of the extreme outer teeth of the combing cylinders 22 as the frame 16 rotates. In view of the fact that the peripheral speed of the bristles of the roller 35 is greater than that of the outer teeth of the individual combing cylinders 22, the bristles of the roller brush which also engage the teeth of the combing cylinders 22 act to brush the nap or waste out of the teeth of these cylinders 22 and transmit it to the teeth of the positively driven combing cylinder 13 upon which it is "packed" by a second roller brush 38 mounted as an idler on shaft 39.

The operation of the machine as above described is as follows: The fiber is fed into the series of clamps by the operator standing on the platform 2, and as the cylinder 3 rotates, the fiber receives its preliminary combing by the cylinders 22 as the frame 16 revolves; and in the act of combing the fibers, if any of the cylinders encounters undue resistance, instead of tearing out the tangled or gnarled fibers, it simply yields on its axis by rotating in a clockwise direction while the frame 16 continues to rotate in an anti-clockwise, thus lessening the strain on the fibers by combing them out more gradually, or only partially combing them, leaving the next succeeding small cylinder to further comb the particular fibers in question before the particular fibers are moved on by the slowly rotating cylinder 3 to the positively driven combing cylinder 13. In this way the rough or preliminary combing of the fibers is accomplished by the yielding cylinders before the fibers reach the other combing cylinders 13 and 12.

Instead of having an integral or rigid combing cylinder such as above described, yielding at its friction bearing, I prefer to use either one of the forms of combing cylinder shown in Figures 2 to 4, inclusive, which consist of sections. Referring to Figures 2 and 3 illustrating the type of individual cylinders 22 shown in Figure 1, 40 is a shaft adapted to be secured from rotation in any suitable manner such for example as by a key 41 securing the shaft rigidly to its support or frame 16 of Figure 1, and this shaft has mounted thereon a

number of combing sections or disks 42 that may be arranged in any suitable manner so that any one of the disks when encountering such undue resistance from the fibers as would unnecessarily cut or break them, may yield about its axis without affecting or unduly affecting the others. These disks are shown in Figure 3 as constructed and arranged on the shaft in the following manner: One end of the shaft has a collar 43 fixedly secured thereon by a pin 44, and between this collar and a second loosely mounted collar 45, I provide a series of balls carried in a ring 46, the parts constituting a thrust bearing. Against the collar 45 is placed an end combing disk 47 which is slipped over the other end of the shaft and is freely mounted on the shaft and may be secured to the collar 45 or not, as is desired. Next to the disk 47 I provide a collar 48 having a key or set screw 49 extending into a longitudinal groove 50 extending along the length of the shaft, so that the collar may be slipped into place over the end of the shaft and is free to move longitudinally of the shaft, but cannot rotate upon the shaft. Between this collar and the combing disk 47 I provide a suitable friction surface. This may be provided in any suitable manner, and I have shown a fiber ring 51 freely mounted in a suitable annular groove 52 formed in the face of the collar 48, so that the disk 47 is free to rotate about the axis of the shaft, provided the frictional resistance between the collar and the disk is overcome. Between this collar and the next combing disk I provide a spiral spring 53 for the purpose of taking up any wear between the faces of the collar and disk, etc. These springs are not secured to the disks or collars, but they rest at one end against the disks and at the other end against the collars.

Each cylinder may have as many of these disks as may be desirable, the disks being say half an inch thick. The division of the cylinder into a number of subdivisions or disks in this manner is very important, because each narrow subdivision or disk can yield when encountering a small local snarl without affecting others, and the narrow disks have relatively small momentum and hence yield more readily, thereby helping to save the fiber. When a suitable number of disks have been placed over the shaft to form a cylinder of the desired length, I screw on a collar 55 having between it and the adjacent disk a friction ring 51, and against this collar I provide a locking nut 56, so that the frictional resistance between the disks and the collars can be regulated by screwing up the collar 55. As the collar 55 is screwed onto the shaft to engage the outer disk, the thrust is transmitted longitudinally of the shaft from each disk to its

adjacent collar, and since these collars are free to slide along the keyway, the thrust is properly distributed and the friction between the different disks thus controlled.

- 5 On one face of each of the sections I preferably provide a thin laterally projecting annular flange 62 with a rounded edge, the function of this being to partially bridge the gap between adjacent combing sections, 10 to reduce the amount of lint or dirt falling between the sections, thus permitting the use of a sufficient working clearance between the adjacent collars and disks for the utilization of the friction rings of suitable size, 15 and protecting the same from the admission of too much dirt or lint. As shown, the edge of the flange is rounded or otherwise suitably arranged so as to reduce friction between it and the surface of the adjacent 20 section if at any time the two should contact. Any suitable means may be provided to permit the disks to separately yield about their axis. For example, instead of using the friction disks just described, I may utilize 25 torsional springs 57, as shown in Figure 4, for partially or wholly replacing the frictional resistance. In this case, as in the case of the combing cylinder just described, a stationary collar 43' is pinned at one end of the 30 shaft, and the shaft is provided with a series of collars 48' having keys 49' fitting in a longitudinal groove 50' formed in the shaft, so that the collars 48' may slide longitudinally of the shaft but cannot rotate there- 35 on; and alternating with these collars 48' a series of combing disks 42' are arranged, these disks, like those just described, being free to yield about the shaft. Each collar 48' is connected to a disk 42' by means of one 40 of the torsional springs 57 which has one of its ends secured to the collar and one to the combing disk. These springs are so chosen and arranged as to give the desired opposition or resistance to the yielding movement 45 of the disks. The adjacent faces of the combing disks may be separated by a small space, as shown.

The area of the engaging surfaces of the hubs 58 of the combing disks 42' with the collars 48' is so small that no undue friction is produced by such engagement; and if desired, the friction can be made practically negligible by any well-known means.

Between the left-hand end disk 42' and 55 the collar 55' which is threaded on the shaft, as heretofore described with respect to Figure 3, I provide a suitable anti-friction device or thrust bearing 59, such as a ball race 60 with balls 61. This collar 55' is locked 60 in position by a nut 56' as heretofore described. Rotating the collar 55' to move it in a right-hand direction reduces the resistance of the torsional spring to the yielding movement.

65 While in Figure 1 I have shown the yield-

ing cylinders operating in a machine in connection with positively driven cylinders, obviously yielding cylinders may be used throughout the machine if desired and mounted and operated in any suitable manner, but I prefer the combination shown and described.

In Figure 6 I have shown another form of machine for combing fiber embodying my invention. This machine, more technically speaking, is known as a fiber-opening machine, and it is arranged and constructed as follows:

At the central upper portion of a main supporting frame 70 there is mounted a 80 large toothed cylinder 71 carried on a shaft 72, having the usual crooked combing teeth 73 embedded in suitable material such as leather stretched around and secured to the periphery of the cylinder. A suitable stationary guard plate or shield 74 surrounds the upper part of the lap cylinder, and this plate is provided with hinged ends 75, 75' hinged in any suitable manner so as to be lifted.

This main cylinder is driven in any well known manner, and on the left-hand side of the frame there is provided an endless conveyer 76 passing over wheels or pulleys 77, 78, one of which is driven in any desired 95 manner for moving the conveyer. On this conveyer is spread, in a well known manner, the fibers or fibrous material to be opened. Between the inner end of the conveyer and the cylinder or roll 71 there is provided two 100 fluted holding or feed rolls 79', 80', which are geared together and suitably driven, as is well understood and as indicated by gears 79''. The layer of fiber is fed by these rolls to two toothed cylinders or rolls 79, 80; known in the strictest sense of the art, as holding or feed rolls. These are mounted one above the other, and each in a well known manner is provided with crooked 105 combing teeth embedded in a suitable cloth or leather stretched around the cylinder as heretofore described in connection with cylinder 71; and the cylinders are spaced apart as is well understood, so that these teeth will engage and feed or hold the layer of fibers coming from the fluted rolls, in position to be engaged by the combing teeth on the lap roller. These teeth on the lap roller engage 110 the fiber and draw it out by such engagement and carry it around with them, all in such 115 manner that the fibers are embedded in the teeth of this lap roll and remain thereon, as is well understood in the art, until a suitable amount of fiber is thus gathered by the lap roller, after which the mat or lap on this roll 120 is cut transversely and one end thereof is then lifted, as is well understood, from the teeth of the lap roller, and inserted between an upper fluted roll 82 and a conveyer 84 125 passing at one end over a lower fluted roll 130

83. The conveyer 84 at its other end passes over a roll 87 mounted on shaft 88. The fluted rolls and conveyer are driven in any suitable manner, as is well understood, in order to convey the lap from the machine.

On the left-hand side of the machine the usual form of toothed stripping cylinder or roll 89 is shown mounted on shaft 90, the operation of which is well understood. This 10 roller serves to clean the teeth of the toothed cylinder 80, as is well understood.

In this machine the toothed cylinders 79, 80 are arranged and constructed according to the form of my invention shown in Figure 2; that is to say, they are in the form 15 of sectionalized toothed cylinders. When these cylinders are so constructed the sections are capable of separately yielding when the fiber that is being acted upon by any of the teeth of the lap roll 71 is put under undue strain. Suppose, by way of 20 illustration, that the lap is three feet wide and the toothed sections on these cylinders 79—80 are an inch wide: If, under these 25 conditions, there is a snarl in the fiber that is engaged by one or two of these toothed sections of the two cylinders 79, 80, then as the teeth on the lap cylinder engage the fiber held by the teeth of these section, the 30 sections may yield so as to relieve the fiber of the sudden tearing strain and thus allow 35 it to be pulled out more gradually. It will thus be seen that in this machine, instead of having the teeth of the yieldable toothed cylinders merely pass through the fibers as 40 described in connection with the machine illustrated in Figures 1 to 5, the teeth of the yieldable toothed cylinders are embedded in the fiber and feed or hold it in such manner that it can yield when it is gripped by 45 the teeth of the revolving lap cylinder, thus effecting a yielding combing operation.

While I have shown and described with particularity three forms of combing cylinders embodying the invention, and have shown the cylinders in one machine as mounted on a rotating frame for combing the fibers, and in another machine arranged to feed the fibers, it will be obvious to those 50 skilled in the art, after understanding my invention, that the cylinders may be arranged in any suitable manner for effecting the desired yieldable combing of the fiber. It is well understood in the art that combing devices, for example, may be mounted 55 on endless chains, etc. The mounting of the cylinders on such supports, and various other modifications and changes in the construction and arrangement of the parts, 60 without departing from the spirit and scope of my invention, will be obvious to those skilled in the art, after understanding my invention, and I aim in the appended claims to cover all such modifications.

65 Having thus described my invention, what

I claim as new and desire to secure by Letters Patent, is:—

1. In apparatus for combing fibers, the combination of a support, a plurality of toothed combing cylinders mounted thereon 70 to respectively yield about their axes when their teeth in the act of combing place the fibers under such tension as to unnecessarily cut or break them, and means for producing motion of said support to cause the cylinders to comb the fiber.

2. In apparatus for combing fibers, the combination of a support, a plurality of combing cylinders mounted thereon to yield 80 about their axes, and separate means for each cylinder for regulating its yielding movement about its axis whereby, when the teeth in the act of combing place the fibers under such tension as to unnecessarily cut or break them, the cylinders may yield about 85 their axes.

3. In apparatus for combing fibers, the combination of a rotatable frame, a plurality of combing cylinders mounted upon said frame, each yieldable about its axis, and 90 frictional means for regulating said yielding movements of the cylinders so that when the teeth in the act of combing place the fibers under such tension as to unnecessarily cut or break them, the cylinders may yield. 95

4. In apparatus for combing fibers, the combination of a rotatable frame, a plurality of combing cylinders mounted thereon concentrically about the axis of rotation of said frame and each mounted to yield about 100 its axis of rotation when its teeth place the fibers being combed under such tension as to unnecessarily cut or break them, adjustable means for each cylinder for regulating its yielding movement, and means for rotating 105 the support.

5. A device for combing apparatus for combing fibers, comprising a number of relatively yieldable toothed rotary elements 110 arranged side by side along the axis of rotation to engage the fiber being combed, the number of toothed elements being such that each element engages only a small portion of the total width of fiber being operated upon, and the yieldability of the 115 elements being such that any element will yield to prevent undue damage to the group of fibers being operated upon by it, whereby unnecessary cutting and breaking of the fibers of localized groups is reduced without substantially interfering with the operation on the remaining fibers of the width being operated upon.

6. A toothed cylinder for combing apparatus for combing fiber made up of a number 125 of toothed annular sections each yieldable about its axis relatively to the others, and having means for regulating such yielding movement.

7. In apparatus for combing fibers, the 130

- combination of a number of toothed annular combing sections mounted concentrically of a common axis and each yieldable about its axis relatively to the others when its teeth 5 place the fibers being combed under such tension as to unnecessarily cut or break them, and means for determining the yielding movement of the sections about their axes.
- 10 8. In apparatus for combing fibers, the combination of a plurality of toothed combing sections mounted concentrically of a common axis, each section being yieldable about its axis relatively to the others, means 15 for each section for opposing its yielding movement, and means for adjusting the effectiveness of said opposing means.
9. In a toothed cylinder for combing apparatus for combing fibers, the combination 20 of a number of toothed sections, a shaft on which said sections are loosely mounted for relative movement about the shaft one with respect to another, means for each section for opposing its yielding movement, and 25 means on the shaft for adjusting the effectiveness of all of said opposing means.
10. In apparatus for combing fibers, the combination of a shaft, a number of toothed annular sections mounted loosely on said shaft and relatively movable about the shaft one with respect to the other, and a number 30 of devices secured to said shaft from relative rotation with respect thereto and respectively yieldably related to the toothed sections for opposing the yielding movement of said sections when they encounter 35 undue resistance.
11. In a toothed cylinder for combing apparatus for combing fibers, the combination 40 of a shaft, a number of toothed annular cylinder sections mounted loosely on said shaft and relatively movable about the shaft one with respect to the other, and a number of devices secured to said shaft from relative 45 rotation with respect thereto and arranged thereon alternately with said toothed sections and engaging the latter frictionally, and yieldable laterally with respect thereto.
12. In apparatus for combing fibers, the 50 combination of a shaft, a number of collars secured to said shaft from relative rotation about the same but movable longitudinally thereof, a number of toothed sections mounted loosely on said shaft and relatively movable about the shaft one with respect to the other and arranged thereon alternately with said collars, a friction surface between each section and an adjacent collar for opposing the yielding movement of said section when 55 it encounters resistance, means on said shaft for regulating the friction between said collars and sections at the friction surfaces, and means for each section operatively related to said section and to an adjacent 60 collar for opposing the yielding movement 65 of said section when it encounters resistance.
13. In apparatus for combing fibers, the combination of a frame for holding fibers to be combed, means for combing said fibers 70 comprising a support with a plurality of combing cylinders mounted thereon each yieldable about its axis, means for producing relative movement between said frame and said support to cause the fibers to be 75 combed by said cylinders, and a combing cylinder adapted to be positively driven about its axis for combing said fibers after they have been combed by said first combing means.
14. In apparatus for combing fibers, the combination of a support, and a toothed cylinder mounted thereon to yield about its axis when encountering undue resistance, said cylinder comprising a plurality of relatively yieldable toothed sections adapted to yield about their axes one relative to the other when the fiber engaged by them is put under undue tension in the combing operation, whereby the sections individually 80 or the cylinder as a whole may yield, depending upon the resistance encountered.
15. In apparatus for combing fibers, the combination of a rotatable frame for holding fibers to be combed, preliminary combing means for combing the fibers comprising a rotatable frame and a plurality of combing cylinders mounted thereon, each yieldable about its axis during the rotation of said frame, and a combing cylinder adapted 85 to be positively driven about its axis for continuing the combing of the fibers.
16. In apparatus for combing fibers, the combination of a rotatable frame for holding fibers to be combed, means for giving 90 said fibers a preliminary combing comprising a rotatable frame with a plurality of combing cylinders mounted thereon, each yieldable about its axis during rotation of the frame, a combing cylinder adapted to be 95 positively driven about its axis for continuing the combing of said fibers after they pass from the first combing means to said cylinder, means for rotating said cylinder-frame and second combing cylinder, a 100 "roller brush" having its teeth adapted to engage the teeth on the plurality of combing cylinders as the frame carrying said cylinders rotates, and also adapted to engage the teeth of the cylinder that does the subsequent combing, the teeth of said "roller brush" being in such intimate mesh with the teeth of the last-mentioned cylinder that the "roller brush" has substantially the same peripheral speed as said last-mentioned cylinder, and the speed of said rotatable frame carrying the plurality of combing cylinders being such that the teeth of said last cylinders where they engage the teeth of said "roller brush" are traveling at less speed 105 110 115 120 125 130

than the peripheral speed of said "roller brush," whereby the fibers adhering to the teeth of said series of roller cylinders are brushed from the same and transmitted to the 5 combing cylinder which does the subsequent combing.

17. In apparatus for combing fibers, the combination of a support, a combing cylinder mounted on said support to yield about 10 its axis, means for producing relative movement between the cylinder and the fiber to be combed for combing the fiber, and adjustable frictional gripping means for regulating the yielding movement of the cylinder about its axis so that when the teeth place the fibers being combed under such tension as to unnecessarily cut or break them, the cylinder will yield about its axis.

18. In apparatus for combing fibers, the combination of a toothed combing cylinder 20 made up of a number of toothed annular combing sections, a support on which said sections are mounted concentrically side by

side, each yieldable about its axis relatively to the others when its teeth place the fibers 25 being combed under such tension as to unnecessarily cut or break them, and means for yieldably connecting said sections to said support.

19. In apparatus for combing fibers, the combination of a toothed combing cylinder made up of a number of toothed annular combing sections, a support on which said sections are mounted concentrically side by 30 side, each yieldable about its axis relatively to the others when its teeth place the fibers 35 being combed under such tension as to unnecessarily cut or break them, and means for yieldably connecting said sections to said support, said sections having lateral annular 40 projections extending from one section to another to exclude lint and dirt.

In testimony whereof, I have signed my name to this specification.

AUBREY E. MEYER.
